UNITED STATES PATENT OFFICE.

MALCOLM WALKER, OF GLASGOW, SCOTLAND, ASSIGNOR TO SMITH AND COVENTRY LIMITED, OF SALFORD, ENGLAND.

DRIVING AND REVERSING APPARATUS.

1,286,162.

Specification of Letters Patent.

Patented Nov. 26, 1918.

Application filed February 29, 1916. Serial No. 81,286.

To all whom it may concern:

Be it known that I, MALCOLM WALKER, a British subject, residing at city of Glasgow, Scotland, have invented certain new and 5 useful Improvements in Driving and Reversing Apparatus, of which the following is a specification.

This invention relates to driving and reversing apparatus applicable for planing 10 machines and other machine tools with a reciprocating table and which may be applied to other machines where a direct and reverse drive are required.

This invention is designed to provide an 15 intermediate mechanical connection between the armature of the magnetic clutches and the shaft and a static brake whereby the shaft may be brought to a standstill when the table of the machine reaches the end of 20 or overruns its traverse. It consists in the particular disposition and arrangement of the parts comprising a pair of annular magnetic clutches rotated in opposite directions with disk or annular armatures and a driven 25 disk or block affixed to the driven shaft with which the armatures are mechanically connected preferably by a spring or resilient connection and to which a brake may be applied.

30 The invention will be fully described with reference to the accompanying drawings.

Figure 1. is an elevation showing the invention applied to the table of a planing machine.

Fig. 2. is a longitudinal section through the clutch.

Fig. 2^a is a plan view of the brush and slip rings.

Fig. 3. is a transverse sectional elevation 40 through the driven disk or block D.

Fig. 4. is a sectional view of the driven disk or block and the brake.

Fig. 5. is a horizontal section taken through the driven disk or block.

Fig. 6 is a side elevation of the machine 45 showing parts in broken line representation.

Fig. 7 is a diagrammatic view of the electrical circuits.

On the driving shaft A of the machine 50 two magnetic clutches B and B' are loosely mounted and free to rotate thereon. The periphery of the driving member of each of these clutches is formed either as a pulley or with teeth and these member of the clutches 55 are continuously driven in opposite direc-

tions by a belt such as C or a pinion such as c. The armatures or driven members b b' of these clutches are loosely mounted on the driving shaft A are disposed thereon adjacent to one another and a driving disk 60 or block D is placed between them. The driving disk or block is made fast by a key d or otherwise to the shaft A and is mechanically connected to the armatures or driven members b b' of the clutches. The 65 connection between the clutch members b b' and the block D may be either rigid or flexible preferably the latter, springs or buffers d' being interposed between lugs d² on the disk or block and lugs b² on the clutch members. 70

In the particular construction shown the driven clutch members or armatures b b' are mounted to rotate upon the bosses d⁴ of the driving disk or block D and this is preferably made of non-magnetic material to insulate the clutches from one another so that the energizing of one clutch may not affect the other. 75

A brake G is applied to the driving disk 80 or block D to be applied electrically at the end of each traverse of the planing machine table E to act as an emergency brake to be applied on failure of the electric current to act to prevent the table E overrunning its 85 traverse in either direction. The brake G is applied by a lever g operated by a magnetic solenoid H or other electrical or mechanical device.

The driving disk or block D is preferably 90 constructed with a number of abutments or lugs to engage the driven members b b' of the clutches. The abutment d² may be formed by inserting plates across an annular groove between two ring flanges d³ on 95 each face of the disk D into the recesses between which lugs or studs b² on the clutch members project, a buffer spring d' being inserted between them to give an elastic or cushion drive. 100

The magnetic clutches B B' may be of any convenient form of high efficiency but at present we prefer clutches the driving members formed, each of an annular electromagnet b³ with the magnetic coil b⁴ fitted into 105 an annular recess b⁵ in the face and a hollow central cone b⁶, and the driven member or annular armature with a friction cone b⁷ projecting from the face to engage the hollow cone of the magnet. The cone or cones 110

are preferably faced with a friction material b^8 such as vulcanized fiber.

A spring b^9 is preferably inserted between the members of each clutch to separate them and the coil is connected to any convenient source of electricity by a suitable device diametrically illustrated as at F.

The two electromagnetic members of the clutches are, when the machine is in operation, continuously driven in opposite directions by belting C, gearing c, or otherwise either applied to their peripheries which may act as pulleys or wheels or they may have pulleys or wheels attached to them, the gearing shaft A being geared to the table E of a planing machine—or to any other machine—by gearing in the ordinary way.

A switch for transferring the current from one clutch to the other is of any convenient form operated or moved at the end of each traverse of the table E by dogs or projections thereon. The preferred form of this switch is shown by Figs. 6 and 7, and the structure and operation thereof will now be described. When the clutch B is energized, the switch arm S is in the left-hand position and makes contact with the plate p connected to the positive of the source of supply and with the plate or terminal p^1 connected with the resistance r' , the latter being connected to the winding of the clutch B. At the point of reversing traverse, however, the switch arm is moved into contact with the terminal p^3 , thereby cutting out the resistance r' . The operation on the right-hand side of the switch connected to the clutch B' through the resistance r^2 is similar to that just explained, except that the switch arm is moved over to engage the plate or terminal p^2 to throw in the resistance r^2 and the current from the source of supply, but at the point of reversing traverse the arm is moved to engage the terminal p^4 to cut out the resistance r^2 .

45 What I claim as my invention and desire to protect by Letters Patent is:—

1. A driving and reversing apparatus applicable to planing and other machines comprising in its construction two magnetic clutches loose on a shaft, one member of each capable of being constantly driven in opposite directions, an armature of each also loose on the shaft, an intermediate driving block fast to the shaft and interposed between the inner ends of the clutches, and means for connecting the armatures with the driving block and for effecting a yieldable drive of the latter, substantially as described.

60 2. In driving and reversing apparatus applicable to planing and other machines the combination of two electric clutches each having an armature a shaft upon which the clutches and armatures are loosely mounted 65 of a driving block interposed between the

inner opposing ends of the two clutches, means for securing the block to the shaft, and means for connecting the clutch armatures with the driving block.

3. In driving and reversing apparatus applicable to planing and other machines comprising in its construction two magnetic clutches loose on a shaft, one member of each capable of being constantly driven in opposite directions, an armature of each also loose on the shaft, an intermediate driving block fast to the shaft between the inner opposing ends of the clutches and projections and abutments on the armatures and on the driving block by which they are connected. 70 75 80

4. A driving and reversing apparatus applicable to planing and other machines comprising in its construction two magnetic clutches loose on a shaft, one member of each capable of being constantly driven in opposite directions, an armature of each also loose on the shaft, an intermediate driving block fast to the shaft projections on the armatures, abutments on the driving block and springs interposed to give a yieldable drive, 85 90 substantially as described.

5. A driving and reversing apparatus applicable to planing and other machines comprising in its construction two magnetic clutches loose on a shaft, one member of each capable of being constantly driven in opposite directions, an armature of each also loose on the shaft, an intermediate driving block fast to the shaft for connecting the clutches to the latter, and a brake applied 95 100 to and controlling the movement of the driving block.

6. A driving and reversing apparatus applicable to planing and other machines comprising in its construction two magnetic 105 clutches loose on a shaft, one member of each capable of being constantly driven in opposite directions, an armature of each also loose on the shaft, an intermediate driving block fast to the shaft, projections on the 110 armatures, abutments on the driving block having connecting coöperation with the projections of the armatures, springs interposed to give yieldable drive, and a brake applied to and controlling the movement of the driving block. 115

7. In driving and reversing apparatus applicable for planing and other machines the combination of two electric clutches having armatures, a driving block interposed between the armatures of the two clutches, means for connecting the clutch armatures to the interposed driving block, and a brake applied to and operable at intervals to control the movement of the interposed block. 120 125

8. In driving and reversing apparatus applicable for planing and other machines the combination of two electric clutches having armatures, a driving block interposed between the armatures of the two clutches 130

and having abutments, projections on the clutch armatures to engage the abutments on the driving block, and springs interposed between the projections and abutments to give yieldable drive.

9. In driving and reversing apparatus applicable for planing and other machines the combination of two electric clutches having armatures, a driving block interposed between the armatures of the two clutches and having abutments, projections on the clutch armatures to connect with the abutments of the driving block, springs between the

projections and abutments, and a brake applied to and operable at intervals to control the movement of the interposed driving block, substantially as and for the purpose described. 15

Dated this 26 day of January 1916.

In testimony whereof I have hereunto set 20 my hand in presence of two subscribing witnesses.

MALCOLM WALKER.
